UNITED STATES PATENT OFFICE.

EDWIN A. BULL, OF CHICAGO, ILLINOIS.

LIGHTING FIXTURE.

Application filed April 18, 1923. Serial No. 632,956.

The object of my invention is the provision of a lighting fixture for illuminating large spaces, such as halls, railway stations and auditoriums, and the principal object is the production of such a fixture whereby the light from the source will be uniformly distributed and diffused.

A further object of the invention is the provision in such a lighting fixture of a diffusing reflector for all rays to be reflected from the source of light and a diffusing reflector for all direct rays from the source to the objects to be illuminated thereby.

Another and further object of the invention is the provision in such a lighting fixture of a reflector and a diffusing member having located therebetween a source of light, the arrangement being such that the source of light cannot be removed without disassembling the parts, whereby theft of the light source is prevented.

I accomplish the above and other objects of the invention by means of a structure such as is shown in the accompanying drawings, in which—

Fig. 1 is a vertical section on the line 1—1 of Fig. 2;

Fig. 2 is a front elevation of the device; and

Fig. 3 is a horizontal section on line 3—3 of Fig. 1.

In the drawings, in which similar reference characters indicate similar elements in all the figures, 1 indicates the lighting fixture support, here shown in the form of a post, such as are commonly employed for street lights; 2 is the source of light; 3 is the reflector; 4 the diffusing glass protector and 5 is an auxiliary source of light.

As shown, the reflector 3 is of general concave curvature in vertical section and of double curvature in horizontal section, each half of the latter curvature having a portion 6 of the form of a generated curve substantially that of a truncated parabola, the space between the outer surface 7 of the reflector and the reentrant portion 8 being for a purpose hereinafter to be set forth.

The edge portions of the reflector are continuous with the parabolic curves 6 and are convex to the source of light which is situated substantially in the plane of the edge portions.

The reflector 3 extends above and below the source of light and forwardly of the same, as shown at 10 and 11 in Fig. 1, pro-

viding flat plates through which the holding rods 12 for the diffusing glass protector 4 extend. This diffusing protector is made of alba glass or similar diffusing material and, as shown, is preferably in three sections having copper strips joining their adjacent edges to which the holding rods 12 are soldered. This diffusing protector serves the purpose of diffusing all direct rays of light from the source and, because of its location and extent with relation to the light source and the reflector, also prevents the removal of the lamp from its socket. As shown in Fig. 3, the diffusing and protecting elements surround at least one-half of the lamp constituting the light source and thus, in connection with the reentrant portion of the reflector, prevent the removal of the lamp when these parts are properly located in their operative positions.

As an additional means for holding the diffusing protector to the reflector, a spring catch 15 or a lock may be employed.

The reflector is made of suitable material having its inner surface white fire enameled, thereby diffusing the light from the source which impinges upon it and is reflected thereby. As shown in Fig. 3, the shape of the reflector is such that the rays impinging upon the reentrant portion are reflected by it far to the sides of the reflector, while those which impinge upon the parabolic portions are directed in substantially parallel directions and those which impinge upon the convex portions are reflected in paths between the two previously referred to sets of rays. The reentrant portion of the reflector is so shaped that the extreme rays therefrom will be substantially 180 degrees apart. Practically none of the reflected rays pass through the diffusing element, thus preventing any undue loss of light. Those rays which pass directly to the diffusing element are refracted and diffused thereby. The light from the source is therefore uniformly distributed in a horizontal direction across a field of substantially 180 degrees and all the rays are reflected or refracted by a diffusing element, no direct unmodified rays proceeding from the light source to the objects to be illuminated thereby.

The reflector may be fastened to the supporting post in any desired manner, but preferably and as here shown, the reentrant portions have integrally formed therewith a sleeve member 15 which surrounds the post.

The reflector may also be provided with an integral upwardly extending portion which provides a housing for the socket for the auxiliary light and also an attaching device for the globe for this light.

The space between the surface 7 of the reflector and the reentrant portion 8 provides a passageway for the cable which extends to the auxiliary light 5. As an obvious modification, the socket for the main source of light might be at the upper portion of the fixture, in which instance, the cable for this light would extend through the passageway referred to, and no auxiliary light would be provided for.

Instead of mounting the fixture upon a post, the reflector element might be provided with vertically backwardly extending portions at the outer edges thereof constituting brackets through which bolts could be threaded whereby the fixture would be fastened directly to a wall or similar support.

It is obvious that certain minor changes might be made without departing from the spirit of my invention, but what I claim as new and desire to secure by Letters Patent is:

1. The combination with a reflector having a reentrant portion of sharp curvature and two similar symmetrically arranged side portions, the radius of curvature of each side portion increasing from the reentrant portion outward for the greater portion of its extent with an outer edge portion of reverse curvature, of a source of light located in front of said reentrant portion substantially in the plane of the edge portions.

2. The combination with a source of light, of a diffusing screen located in front of and partially surrounding said source, and a diffusing reflector consisting of two similar portions symmetrically arranged with respect to the source of light and meeting at a point directly behind said source and presenting to the source continuous reflecting curves which cause the rays returned thereby to pass to the sides of said source of light and said diffusing screen without impinging thereon.

3. The combination with a lamp, of a diffusing reflector consisting of two similar segments symmetrically arranged with re-

spect to the lamp and meeting at a point directly behind the said lamp and a diffusing element directly in front of said lamp of less lateral extent than said reflector, the space between the sides of the diffusing element and the reflector being less than the diameter of the lamp while permitting the passage therethrough of all reflected rays.

4. The combination with a source of light, of a reflector consisting of two similar portions symmetrically arranged with respect to the source of light and meeting at a point directly behind said source of light, constituting a reentrant portion, and an auxiliary source of light located above said first mentioned source of light and said reflector and power conducting means for said auxiliary source of light located in the space provided by said reentrant portion.

5. The combination with a source of light, of a diffusing reflector located in the rear of said source of light, said reflector being concave in vertical section and of double curvature in horizontal section, the outer vertical portion of said reflector being convex to the source of light.

6. The combination with a source of light, of a diffusing reflector located in the rear of said source of light, said reflector being concave in vertical section and of double curvature in horizontal section, the outer vertical portion of said reflector being convex to the source of light, and a diffusing refractor located in front of said source of light and attached to said reflector, said refractor being of less lateral extent than said reflector, the spaces at the sides therebetween being less than the diameter of the source of light.

7. The combination with a reflector having a reentrant portion of sharp curvature and two similar symmetrically arranged side portions, the radius of curvature of each side portion increasing from the reentrant portion outward and having an outer edge portion of reverse curvature, of a light source situated in front of said reentrant portion, the curvature of the reflector being such that the rays from the light source reflected thereby are directed away from the source of light.

In testimony whereof, I affix my signature.

EDWIN A. BULL.
